ATTORNEY.

UNITED STATES PATENT OFFICE

NILS GUSTAV OLSON, OF BOSTON, MASSACHUSETTS, ASSIGNOR OF ONE-HALF TO
KARL G. HEED, OF CHICAGO, ILLINOIS

OIL CAN

Application filed May 11, 1928. Serial No. 276,914.

This invention relates to improvements in oil cans and more particularly to oil cans of the diaphragm bottom type so constructed as to permit the projection of a jet of oil from the can spout in any and all positions of the can.

A further object is to provide an oil can of this type that will not leak oil regardless of the position of the can, that is durable in construction and positive and efficient in operation.

With the foregoing and other objects in view the invention consists in the combination and arrangement of parts to be hereinbelow after fully described, pointed out in the appended claims and illustrated in the accompanying drawing which forms a part of this application and in which—

Fig. 1 is a vertical sectional view of the can in elevation.

Fig. 2 is a similar view but in inverted position showing the automatically altered position of certain of the relatively movable parts.

Fig. 3 is a fragmentary sectional view of the can in a position at right angles to Figs. 1 and 2.

Like reference characters denote corresponding parts throughout the several views.

The present can makes use of a gravity controlled spout section which will follow the liquid contents of the can as the position of the can is changed thus making it possible to evacuate the liquid contents of the can in any and all positions of the same.

The reference numeral 1 denotes the body of the can of conventional shape and provided with the integral diaphragm bottom 2. The neck 3 of the can is threaded externally to receive the threaded cap 4 in a perforation in which the air intake cylinder 5 is arranged, the air hole 6 being normally closed by the ball valve 7 yieldingly closing same through the medium of the spring 8.

Also carried in said cap 4 is the exterior spout section 9 having a perforate partition 10 that serves as a seat for the spring 11 that yieldingly retains the ball valve 12 seated upon the upper end of the interior spout section 13 operatively fitted into the

inner end of the section 9, said spout section 13 having the elbow 14 adjustably secured thereto by the swing joint 15, a second swing joint 16 at the opposite end of said elbow 14 adjustably carrying the gravity controlled spout section 17.

The contents of the can keep the spout sections and joints well lubricated so that they move easily and as the body of the can is inclined, tilted or turned in one or another direction the gravity controlled spout section 17 will follow the liquid contents and its free end will be constantly immersed therein so that evacuation of said contents through the spout sections 17, 13, 9 and connections is always possible by means of the diaphragm bottom in the usual manner. The ball valves 7 and 12 effectually prevent leakage of the contents of the can in any position of the same.

What is claimed is:—

1. In an oil can comprising a diaphragm bottom, a cap having a valved passageway, a spout comprising an outer section, an intermediate section and an innermost section, said innermost section being L-shaped, an L-shaped elbow pivotally connecting said innermost section to said intermediate section, and a ball valve yieldingly closing one end of said intermediate spout section.

2. In an oil can comprising a diaphragm bottom, a cap having a valved passageway, a spout comprising an outer section, an intermediate section and an innermost section, said innermost section being fixedly secured to said outer section, said innermost section being L-shaped, an L-shaped elbow pivotally connecting said innermost section to said intermediate section, and a ball valve yieldingly closing one end of said intermediate spout section.

3. In an oil can comprising a diaphragm bottom, a cap having a valved passageway, a spout comprising an outer section, an intermediate section and an innermost section, said innermost section being fixedly secured to said outer section, a ball valve yieldingly closing one end of said intermediate spout section, said innermost section being of rectangular formation, and a rectangular elbow

pivots connecting said intermediate section and said innermost section whereby to form, with said members, a continuous and uninterrupted passageway.

5 In testimony that I claim the foregoing as my own I have hereto affixed my signature.

NILS GUSTAV OLSON.
